UNITED STATES PATENT OFFICE.

FREDERICK W. WILSON, OF ELMHURST, NEW YORK.

ILLUMINATED SIGN.

1,228,507.

Specification of Letters Patent.

Patented June 5, 1917.

Application filed January 26, 1916. Serial No. 74,340.

To all whom it may concern:

Be it known that I, FREDERICK W. WILSON, a citizen of the United States, residing at Elmhurst, Long Island, in the county of 5 Queens and State of New York, have invented new and useful Improvements in Illuminated Signs, of which the following is a specification.

This invention relates to improvements in 10 illuminated signs of the type wherein a globe bearing suitable legends, or advertisements incloses a source of illumination, and has as its object to provide a sign which is very compact and which presents a neat and 15 attractive appearance.

Other objects of my invention are to provide a sign, the parts of which may be readily assembled and taken apart, the globe particularly being detachable in a quick and 20 easy manner, so that access may be had to the source of light within the same. My sign may be manufactured at relatively low cost; has a very practical construction, and consists of relatively few parts.

25 The above and other objects of my invention are obtained in the structure described in detail in the following specification and illustrated in the accompanying drawings wherein,—

30 Figure 1 is an elevational view of my improved sign and bracket therefor.

Fig. 2 is a longitudinal section through the sign and bracket shown in Fig. 1.

Fig. 3 is a vertical cross-section taken on 35 line 3—3, Fig. 2.

Fig. 4 is an enlarged fragmentary sectional view through a modified form of bracket.

Fig. 5 is an elevational view of the various 40 parts or elements of my improved sign the same being shown disassembled.

Fig. 6 is a perspective view of one-half of the split collar.

Referring to the drawings, wherein like 45 numerals represent like parts in the several views, 10 is a pipe or hollow tube which is screw-threaded throughout its length and which serves as the leading-in conduit for the electric conductors 11 connected in the usual manner to an ordinary lamp socket 12 which is screw-threaded upon the inner end of the tube or pipe, and which socket receives an electric-light bulb 13. The electric-light bulb may be of a kind ordinarily used 55 for house lighting, or it may be of the well-

known flash type, which alternately lights up and goes out so that the attention of the observer is quickly attracted.

14 designates a canopy or cap which may be of any suitable form, and which may be 60 ornamented as desired. The canopy is here shown as being somewhat conical in shape and as having a boss 15 at its apex which has a through opening suitably threaded to receive the screw-threaded tube 10, a lock nut 65 16 being provided upon the tube 10 to secure the canopy 14 in adjusted position thereon. The base or globe-receiving member preferably comprises a member having a circular plate 17 adapted to engage in the 70 open end of the canopy, and a substantially cylindrical portion 18 over which the open end of the electric-light globe 19 is adapted to pass. The plate 17 has an opening at its center, which opening is properly threaded 75 to receive the tube 10, so that the base may be screwed into proper position upon the tube 10. The base or globe-receiving member may be constructed in any suitable manner, and the plate 17 and portion 18 may be 80 integral, but preferably I form the same of the circular plate 17, which is suitably stamped or spun to provide a cylindrical boss or projection 20 which is received by and secured to the portion 18. The member 85 18 preferably tapers inwardly toward its own axis, so that it is slightly frusto-conical, and it is encircled by a suitable compressible padding 23 of fabric, paper, or the like. The globe 19 is reduced in diameter adjacent its 90 open end to provide a neck as at 21, and a bead or flange 22. The globe may, of course, be of any desired shape or configuration, but I have shown the same as being polygonal in cross-section, and preferably it is hexagonal, so that plane surfaces are presented 95 which are to bear the desired legend, name or advertisement. When the globe is brought down on the base or globe supporting member the neck of the globe fits tightly 100 about the portion 18, and as the portion 18 is tapered, it acts as a wedge therein so that wobbling or lateral displacement of the globe relative to the base is well guarded against.

105 The clamping member or the means for retaining the globe upon the base or globe-supporting member comprises a split collar 24 which is divided into two similar semi-circular parts as is best disclosed in Fig. 6. 110

The collar 24 may be spun or stamped as desired, and it is provided with a bead 25 which forms a circumferential groove adapted to inclose or receive the bead 22 of the 5 globe 19, and the collar is further provided with an inwardly bent circumferential flange 26 which is adapted to encircle or overlap about the edge of the plate 17 of the base or globe-supporting member, as will be seen from Fig. 2.

It will be seen that to assemble the parts of the sign so far described, the base or globe-supporting member may first be screwed onto the tube or pipe 10. A lock 10 nut 26' is then turned up on the tube 10 against the face of the boss 20 to retain the base in adjusted position and to strengthen or reinforce the plate 17. The socket 12 together with the bulb 13 is next positioned on 15 the end of the tube. The canopy 14 may be screwed onto the pipe, but not up to the base and the globe is inserted upon the base or supporting member with the neck thereof fitting tightly about the portion 18 and with the mouth or open end of the globe 25 engaging against the face of the flange of the plate 17. The collar is then placed upon the neck of the globe with bead or groove 25 of the collar receiving the bead 22 of the 30 globe and with the flange 26 encircling or engaging about the edge of the plate 17. The canopy 14 is then turned relative to the tube 10 to bring its open end or mouth into engagement with the split collar 24 and thus 35 the members of the split collar are forced radially inwardly and locked in place to secure the globe to the base or globe-supporting member. The lock-nut 16 is then turned up on the tube against the canopy to lock the latter in adjusted position.

In the drawings, I have disclosed a peculiar form of bracket for supporting my sign which comprises a base plate 27 suitably provided with screw-receiving holes, or 40 the like, 28, whereby the bracket may be secured to a wall, pillar, or other structure. Extending outwardly from the base plate is a boss or arm 29 having a transverse aperture 30, the arm being provided with a central screw-threaded opening to receive the 45 end of the tubular member 10. The tube 10 is adapted to extend through the arm 29 and protrude into the aperture 30, so as to receive suitable nuts 31 to lock the tube against 50 rotation.

It is, of course, to be understood that the construction of the bracket may be varied as desired, and in Fig. 4, I have disclosed a slight modification wherein the base plate 60 27 is provided in alignment with the opening in the boss 29 with an aperture as at 32, to permit the pipe 10 to extend entirely through the bracket. In making connection through a wall, or the like, the electric conductors are entirely housed, and cannot be

seen, and if desired, the protruding end of the tube 10 may be of sufficient length to extend through the wall of the structure to which my sign is secured. I have found the bracket shown by me to be peculiarly adapted for use in combination with my sign for by so constructing the bracket it can be attached to the corner of a house, window, sash, or the like, without interfering with adjacent protrusions or obstructions. 75

It will be noted that the various elements or parts of which my sign is composed are all mounted upon and tied together by a single member or tube 10 which tube serves as a leading-in conduit for the electric-wires or 80 conductors, and, furthermore, the tube constitutes the means for connecting or attaching the sign to the bracket. The parts of which my improved sign is composed may be readily taken apart, it being merely necessary to unscrew the same from the tube or pipe 10. Access may be readily had to the interior of the sign for purposes of renewing the bulb, or the like, by merely unscrewing the canopy to withdraw the same from 85 engagement with the split collar, and after removing the collar from its position the globe may be lifted from the base supporting member. The globe is securely locked upon the base supporting member in such 90 manner that water, dirt, and the like cannot have access to the interior of the globe and the globe is maintained in place without the usual frame or supporting members extending through the same. 95

It is, of course, understood that my device is susceptible to various changes and modifications which would be within the spirit of the invention without departing from the scope of the following claims. 100

What I claim is:—

1. In combination, a globe, a globe-supporting member, a collar adapted to encircle one end of said globe and overlap said globe-supporting member, and a cap movable longitudinally of the globe supporting member and encircling and engaging about said collar to lock the same in place and retain that portion of the collar encircling the end of the globe in clamping position thereabout. 110

2. In combination, a globe, a globe-supporting member, a collar adapted to encircle one end of the globe and overlap said globe-supporting member, and a cap movable to and from said collar and encircling and engaging that portion of the collar which encircles the globe to retain the collar in clamping position thereabout. 120

3. In combination, a globe having an open end, a globe-supporting member having an outwardly projecting portion extending into and engaging the inner walls of the open end of the globe, said outwardly extending portion having substantially the same external dimensions as the internal dimensions of the 125 130

open end of said globe to form an enlarged bearing surface between the globe and said outwardly extending portion, a collar adapted to engage about one end of the globe and overlap said globe-supporting member, and means for locking said collar in position.

4. In combination, a globe having an open end, the opening through which is substantially of uniform diameter throughout, a globe-supporting member having an outwardly projecting portion of substantially the same diameter throughout as the opening in the open end of said globe, said projecting portion being circular in cross-section, said globe being adapted to be inserted over the outer end of said outwardly extending portion of the globe-supporting member, a collar encircling one end of the globe and overlapping said supporting member, and a cap engaging said collar to lock the same in position.

5. In combination, a globe, a globe-supporting member having a tapering portion adapted to extend into and fitting the open end of the globe, a split collar adapted to encircle said globe adjacent its open end and overlap said globe-supporting member, and a cap for locking the collar in position.

6. In combination, a globe, a globe-supporting member having a tapering portion circular in cross-section and extending into and fitting the open end of the globe and a flange portion against which the open end of the globe is adapted to abut, a split collar adapted to encircle the globe adjacent its open end and overlap the flange portion of said globe-supporting member, and a cap for locking the parts of the collar in place.

7. In combination, a globe having a reduced or neck portion adjacent one end and a bead at the open end thereof, a globe-supporting member having a portion adapted to fit in the open end of the globe and a flange portion against which the open end of the globe is adapted to abut, a split collar having a groove adapted to receive the bead of the globe and a flange adapted to encircle the flange portion of said globe-supporting member, and a cap engaging about said collar for locking the parts of the collar in place.

8. In combination, a globe, a rod or tube, a globe-supporting member upon said tube, a collar adapted to encircle one end of said globe and overlap said globe-supporting member, and a cap adjustably mounted on said rod or tube independently of said globe supporting member and adapted to engage about said collar to retain the same in position.

9. In combination, a globe, a connecting member, a source of illumination mounted on said connecting member, a globe-supporting member adjustably mounted on said connecting member, means for securing the

globe and globe-supporting member against relative displacement, and a cap adjustably connected to said connecting member adapted to engage said securing means.

10. In combination, a connecting member, a source of illumination on one end thereof, a globe, a globe-supporting member adjustably mounted on said connecting member, means for securing the globe and globe-supporting member against relative displacement, a cap adjustably mounted on said connecting member and adapted to engage said securing means, and means mounted on said connecting member for locking said cap against displacement.

11. In combination, a connecting member, a source of illumination mounted thereon, said connecting member serving as a leading-in conduit for the supply of illuminating energy to said source of illumination, a globe, a globe-supporting member mounted on said connecting member, means for securing the globe and globe-supporting member against relative displacement, and a canopy adjustably mounted independently of said globe supporting member on said connecting member and adapted to lock said securing means in position.

12. In combination, a globe, a hollow tubular member screw-threaded throughout its length, an electric-light mounted on the end of said tubular member, conductors for said light passing through said tubular member, a globe-receiving member screw-threaded on said tubular member and comprising a cylindrical portion adapted to be inserted in the open end of said globe and a flange portion against which the open end of the globe is adapted to abut, a split collar adapted to encircle the globe adjacent its open end and to overlap said flange portion of the globe-supporting member, a canopy screw-threaded on said tubular member and adapted to receive or encircle at its open end said split collar to retain the same in locking position, and a lock-nut screw-threaded on said tubular member for locking said canopy in adjusted position.

13. In combination, a connecting member, a source of illumination mounted thereon, a globe about said source of illumination, a globe-supporting member mounted on said connecting member, means for securing the globe and globe supporting member against relative displacement, a canopy mounted on said connecting member and adapted to lock said securing means in position, and a bracket adjustably mounted on the end of said connecting member.

14. In combination, a tubular member, an electric-light mounted on the end of said tubular member, conductors for said light passing through said tubular member, a globe-supporting member screw-threaded on said tubular member, a globe, means for se-

curing the globe and globe-supporting member against relative displacement, a canopy screw-threaded on said tubular member and adapted to engage said securing means to 5 lock the same in position, and a bracket screw-threaded on the end of said tubular member.

15. In combination, a tubular member screw-threaded throughout its length, a 10 source of illumination mounted thereon, said tubular member serving as a leading-in conduit for the supply of illuminating energy to said source of illumination, a globe, a globe-supporting member adjustably screw-threaded on said tubular member, means 15 for securing the globe and globe-support-

ing member against relative displacement, a canopy screw-threaded on said tubular member and adapted to lock said securing means in position, and a bracket comprising a base portion provided with means for securing the same to a suitable support and an arm having a threaded opening to receive the end of said tubular member. 20

In testimony whereof I have hereunto set 25 my hand in presence of two subscribing witnesses.

FREDERICK W. WILSON.
